INCINERATOR SPARK ELIMINATOR
Charles Rumpel, 32151 Old Yale Road, Clearbrook,
British Columbia, Canada
Filed Aug. 13, 1962, Ser. No. 216,598
5 Claims. (Cl. 110—119)

This invention relates to a device for eliminating the discharge of sparks and other solid products of combustion from an incinerator.

In many agricultural and industrial operations it is common practice to dispose of combustible waste products by burning them in open-air burners or incinerators many of which are in the form of simple steel drums. The carrying on of such practices particularly without proper smoke and spark control, causes severe air pollution in the locality involved as a result of the discharge of smoke and solid particles of burned and partly burned materials. In addition to this most undesirable effect, even more serious dangers result from the discharge of burning particles in areas where there is substantial fire risk. Notwithstanding these known dangers, it has often been common to attempt disposal of combustible waste materials by burning them in open-top steel drums or other primitive incinerator arrangements without adequate smoke and spark control.

While there have been numerous prior proposals for the design of incinerator devices having proper smoke and spark control, all these, as far as I am aware, have taken the form of relatively complicated structures in many cases useful only in connection with a burning chamber of special design. It would therefore be of substantial advantage, and is accordingly an object of my invention, to provide a relatively simple smoke and spark control device which can be applied to almost any form of container adapted for the burning of refuse, and which in particular can be used in connection with steel oil drums of cylindrical configuration which are commonly used for this purpose.

I have found that it is possible to design a satisfactory spark eliminator and smoke control device for use in connection with a simple form of incinerator by providing a main body member adapted to enclose the top of the incinerator so as to effect air-tight engagement with the periphery thereof. A stack is centrally disposed in the body member so as to project both downwardly into the incinerator and upwardly above the body member. A baffle member is disposed immediately below the lower end of the stack, within the incinerator, so as to require the products of combustion to travel in generally horizontal direction immediately prior to entering the stack. Similarly, a hood member is disposed on the upper end of the stack whereby the products of combustion are discharged from the stack in a generally downward direction.

In preferred embodiments of my invention adapted particularly for use with common circular steel drums I provide a body member, stack and hood of generally circular cross-section in planes parallel to the top of the incinerator. The body member curves upwardly from its point of engagement with the top of the incinerator to the point where the stack passes through it at a central location. The baffle member is in the form of a steel plate disposed below the lower part of the stack, and the hood comprises a hemispherical top section having around its edge an inwardly inclined annular flange defining, with the outside of the stack, a somewhat restricted annular outlet to the atmosphere for the products of combustion.

My invention will be described in detail in conjunc-

2

tion with the attached figures of drawings, illustrative of a preferred embodiment thereof, in which:

FIGURE 1 is a top plan view of a device made in accordance with my invention, and

5 FIGURE 2 is a cross-sectional view taken along the lines II—II of FIGURE 1.

Referring to the drawings, the body member 10 is shown as being in the form of a segment of a sphere, the convex surface of which faces downwardly into the incinerator. Along the bottom of the body member 10 are arranged annular flanges 20 and 21 disposed at right angles to each other which are adapted to effect with the top of the incinerator a substantially air-tight joint.

10 A stack 12 is disposed in the body member 10 so as to pass through it at its highest point 11 so that it is maintained in a vertical position with its axis more or less in line with the axis of the incinerator. The lower end 21 of the stack is, in the embodiment shown, positioned below the base of the body member by a distance 15 K as shown. Disposed below this lower end is a baffle member 13 comprising a plate attached to the lower end of the stack by a plurality of supports 22 disposed around the periphery of the plate and the stack at convenient locations dictated by the need for structural 20 strength. Between the supports 22 are spaces 23 which permit the products of combustion to pass between the edges of the baffle 13 and the lower end of the stack and thus gain access to the latter.

25 To the upper end of the stack a hood generally represented by 15 is mounted in the particular embodiment illustrated. The hood 15 comprises a hemispherical sector 24, around the lower edges of which is mounted a downwardly and inwardly inclined annular flange 25.

30 The hood 15 is mounted on the upper end of the stack by means of supports 26 so that parts of the hood extend downwardly around the outer periphery of the stack. These supports 26 define spaces 27 between them which permit the products of combustion emerging from the 35 upper end of the stack 12 to pass downwardly between the inside surface of the hood 15 and the outside surface of the stack 12 and thence, through the annular opening defined by flange 25, to the atmosphere.

30 Should it be desired to permit additional air to enter 45 the incinerator assembly so as to effect complete combustion, it would be possible to provide vents which permit the introduction of secondary air into the stack. Such vents 28 would preferably be disposed around the 50 stack just above the point 11 where it emerges from the body member 10.

45 It will be observed from the arrows 30, 31, 32 and 55 33 that the products of combustion produced in the lower part of the incinerator are forced to change direction through substantially 180 degrees several times in order to reach the atmosphere from inside the incinerator. This 60 labyrinth-like path, and in particular the effect of the centrifugal force on solid particles in the gases caused by these changes in direction assists in removing these particles from the gases and also, because of the greater time required to reach the atmosphere, helps to effect more complete combustion. If in the circumstances of any particular case it is desired to effect more changes in direction of the products of combustion than is provided for in the embodiment illustrated, this could 65 of course be brought about by the use of additional hoods and stacks.

60 In the drawing the baffle 13 is shown as being in the form of a flat circular plate. I have found, however, that an inverted cone will also give satisfactory results. Similarly, while it is usually easiest to use a circular stack, other cross-sectional shapes will be found satisfactory.

70 A wide variety of materials can be used for fabricating

the various parts of my spark eliminator device so long as they are suitable for controlling combustion and for the particular fuels or refuse being burned.

I have found that substantial variation can be tolerated in the relative dimensions of parts of my spark eliminator without sacrificing adequate performance.

Experimentation has, however, revealed that for satisfactory operation the relative sizes of the respective parts should be kept within the limits shown in the chart hereunder. In this chart I also give the relative sizes for a particular spark eliminator device made in accordance with my invention which has yielded particularly satisfactory results, these are given under the column marked "optimum."

The dimensions given in the chart are all related to the size of an incinerator having a circular top of diameter 5D, D representing the diameter of the stack:

Part	Maximum	Minimum	Optimum
(a) Diameter of the stack.....	0.1D	4.5D	D
(b) Diameter of the baffle member.....	1.1D	4.75D	2D
(c) Total stack length.....	D	50D	4D
(d) Proportion of length of stack above body member.....	0.1	0.9	0.5
(e) Distance of baffle member below stack.....	0.5D	5D	0.25D
(f) Distance from top of stack to bottom of annular flange.....	0.2D	10D	0.75D
(g) Distance between bottom of stack and top of incinerator.....	Nil	45D	0.5D
(h) Maximum hood diameter.....	1.1D	10D	1.1875D
(i) Diameter of outlet formed by annular flange.....	1.1D	10D	2D

What I claim as my invention is:

1. A spark eliminator for an incinerator comprising: a main body member adapted to enclose the top of the incinerator so as to effect substantially air-tight engagement with the periphery thereof, said body member being of substantially curved cross-section with the concave surface adapted to face into the incinerator; a stack centrally disposed inside the body member so as to project above the body member and a substantial distance below the body member, said stack being open at lower and upper ends thereof respectively to form an entrance and an outlet; a baffle member in the form of a flat plate spaced immediately below the lower end of the stack and extending across the entrance thereof and shaped so as to require the products of combustion to travel in a generally horizontal direction immediately prior to entering the stack, a plurality of spaced supports suspending said baffle member below the lower end of the stack, said plate being of area larger than the stack whereby the products of combustion are forced to pass between said supports before entering the stack; and a hood member disposed on the upper end of the stack spaced from and extending over the outlet thereof and shaped to direct the products of combustion from the stack in a generally downward direction, said hood member being of inverted, cup-shaped form and being attached to the upper end of the stack by a plurality of support members having spaces therebetween, said spaces permitting the products of combustion emerging from the stack to pass downwardly between the outside of the stack and the inside of the hood past the periphery thereof and thence into the atmosphere; whereby the products of combustion produced in the lower part of the incinerator are forced to change direction through substantially 180 degrees several times in order to reach the atmosphere, thus tending to remove solid particles from the gases and to effect more complete combustion.

2. A device as claimed in claim 1 wherein the periphery of the body member is provided with downwardly and outwardly projecting flanges, adapted to effect engagement with the periphery of the top of the incinerator.

3. A device as claimed in claim 1 adapted for use in conjunction with an incinerator having a circular top, wherein the body member, stack and hood are of circular cross-section in planes parallel to the top of the incinerator and wherein the baffle member is a circular plate.

4. A device as claimed in claim 1 adapted for use in conjunction with an incinerator having a circular top of diameter 5D, wherein the body member, stack and hood are of generally circular cross-section in planes parallel to the top of the incinerator, the hood being of inverted hemispherical configuration with an inwardly inclined annular flange disposed on its lower end, the stack being of cylindrical configuration and the baffle member being a circular plate, and wherein the following dimensional relationships exist, D representing the diameter of the stack:

- (a) diameter of the stack: between 0.1D and 4.5D
- (b) diameter of baffle member: between 1.1D and 4.75D
- (c) total stack length: between D and 50D
- (d) proportion of length of stack above body member: between 0.1 zero and 0.9
- (e) distance of baffle member below stack: between 0.5D and 5D
- (f) distance from top of stack to bottom of annular flange: between 0.2D and 10D
- (g) distance between bottom of stack and top of incinerator: between zero and 45D
- (h) maximum diameter of hood: between 1.1D and 10D
- (i) diameter of outlet formed by annular flange: between 1.1D and 10D

5. A device as claimed in claim 1 adapted for use in conjunction with an incinerator having a circular top of diameter 5D, wherein the body member, stack and hood are of generally circular cross-section in planes parallel to the top of the incinerator the hood being of inverted hemispherical configuration with an inwardly inclined annular flange disposed on its lower end, the stack being of cylindrical configuration and the baffle member being a circular plate, and wherein the following dimensional relationships exist, D representing the diameter of the stack:

- (a) stack diameter: D
- (b) diameter of baffle member: 2D
- (c) total stack length: 4D
- (d) proportion of length of stack above body member: 0.5
- (e) distance of baffle member below stack: 0.25D
- (f) distance from top of stack to bottom of annular flange: 0.75D
- (g) distance between bottom of stack and top of incinerator: 0.5D
- (h) maximum diameter of hood: 1.875D
- (i) diameter of outlet formed by annular flange: 2D
